UNITED STATES PATENT OFFICE.

JOHNSON MORRIS WILLIAMS, OF PARKER, ARIZONA TERRITORY.

CLOTHES-PIN.

1,003,842.

Specification of Letters Patent. Patented Sept. 19, 1911.

Application filed May 23, 1910. Serial No. 563,027.

To all whom it may concern:

Be it known that I, JOHNSON MORRIS WILLIAMS, of Parker, in the county of Yuma, Territory of Arizona, have invented 5 a new and useful Improvement in Clothes-Pins; and I do hereby declare that the following is a full, clear, and exact description of the same.

This invention relates to clothes pins of 10 that type embodying movable jaws normally held closed by a spring interposed between the jaws, and the primary object of the invention is to provide a clothes pin wherein the several components are constructed from 15 a single piece of material bent into shape to form two jaws which have portions continuous with an interposed coil serving not only as means for maintaining the jaws normally closed, but also as a resilient fulcrum means 20 for the two jaws.

A further object of the invention is to provide a clothes pin having movable resiliently controlled jaws which may be readily applied over an article hung on a clothes 25 line and reliably fix the said article with such resistance as to overcome any tendency to disengagement while the pin is applied thereto.

The invention consists in the construction 30 and arrangement of the several parts which will be more fully hereinafter described and claimed.

In the drawing: Figure 1 is a perspective view of a clothes pin embodying the features 35 of the invention. Fig. 2 is an edge elevation thereof shown applied.

The improved clothes pin comprises three essential components consisting of two jaws 5 and 6, each having clamping extremities 7 and handle extremities 8, and an interposed coil 9 which operates to normally hold the clamping extremities 7 of the jaws in close 40 relation and also as a resilient fulcrum means to permit the jaws to be opened by 45 pressing the handle extremities 8 toward each other. The entire clothes pin is made up of a single piece of material, preferably wire, having an inherent resiliency, and the clamping and handle or pressure extremities 7 and 8 of each jaw are constructed in 50 the form of open loops of approximately triangular form and contracted at the center and fixed by one end 10 of the wire which is

firmly bent therearound in a plane at right angles thereto. Both jaws are similarly constructed and the wire is continued from one jaw to the other at a point above or in rear of the secured extremities 10 of the two jaws, one side member 11 of each jaw being extended above or in rear of the secured 55 ends or extremities 10 and formed into the coil 9 which is disposed centrally with relation to the openings of the handle extremities 8 and in a plane at right angles to the latter so that when the handle extremities 60 are contracted or pressed together the coil 9 will not interfere with the movement of the said extremities. By arranging the coil 9 as just explained, an effective resilient action is set up with relation to the clamping 65 extremities 7 and the latter together with the handle extremities 8 are also maintained in regular positions relatively to each other.

To render the clamping extremities 7 effective in securing articles of clothing on a 70 line and to maintain the pin in reliable applied position, they are provided with outward bends 12 to form seats which unitedly have less maximum dimensions than the dimension of the clothes line and article applied over the line, as clearly indicated by 75 Fig. 2.

The pin as an entirety may be suitably plated to avoid corrosion or oxidation, or the wire may be primarily of such character 80 as to be non-corrosive. Any suitable means may be employed for forming the pin, and changes in the proportions and dimensions may be adopted at will.

What is claimed as new is:

A clothes pin comprising two jaws each embodying a clamping and an operating extremity, both jaws being intermediately contracted and secured by the terminals of the material of which the pin is formed by 90 closely looping said terminals around the contracted portions and the jaws also each having a member projecting from and continued into an intermediate coil located between and disposed in planes at right angles 95 to the operating extremities of the two jaws and serving as a resilient means to retain the clamping extremities in normally closed position and also operating as a fulcrum for said jaws, the jaws and operating extremities being each of open loop construction 100

and the coil arranged centrally with relation to the open portions of the operating extremities so as to permit the latter to have a free compressing operation by clearing the coil which projects thereinto when said operating extremities are compressed, the clamping extremities at a distance inwardly

from their free ends being provided with inner opposing seats.

JOHNSON MORRIS WILLIAMS.
